UNITED STATES PATENT OFFICE.

ABE LINCOLN CUSHMAN, OF CONCORD, NEW HAMPSHIRE.

CENTRIFUGAL SWITCH.

1,317,757.

Specification of Letters Patent.

Patented Oct. 7, 1919.

Application filed January 14, 1915. Serial No. 2,254.

To all whom it may concern:

Be it known that I, ABE LINCOLN CUSHMAN, a citizen of the United States, and resident of Concord, in the county of Merrimack and State of New Hampshire, have invented new and useful Improvements in Centrifugal Switches, of which the following is a specification.

This invention relates to centrifugal switches, and particularly to centrifugal switches for alternating current motors of the single phase induction type having a stator provided with two windings, one of which may be termed the auxiliary or starting winding and the other the main or running winding. When the motor is first started both of the windings are in circuit with the main supply wires and act in conjunction; but when the motor has acquired a certain speed the starting winding is automatically cut out leaving the running winding only connected to the mains.

Devices for automatically cutting out the starting winding through the action of the so-called centrifugal force of rotation are well known, and the present invention has to do principally with improvements in the construction and operation of the centrifugally actuated contact making and breaking members for controlling the circuit of the starting winding. Other features will hereinafter be described and particularly pointed out in the claims.

In the accompanying drawings which illustrate one embodiment of the invention,—

Figure 1 is an elevation of the centrifugally actuated contact members, the brushes, and the insulating ring on which they are carried, showing the contact members in starting position;

Fig. 2 is a vertical, central section of the parts shown in Fig. 1, together with associated parts of the motor;

Fig. 3 is a view similar to Fig. 1, but taken on a plane through line 3—3 of Fig. 2, showing the contact members in running position;

Fig. 4 is a top view of the upper plate carrying the upper brush and contact member;

Fig. 5 is a detail view showing the upper plate and brush holder in side elevation;

Fig. 6 is a detail view showing the lower plate and brush holder in side elevation; 55

Fig. 7 is a top view of the lower brush holder; and

Fig. 8 is a diagrammatic view illustrating the wiring, and showing the contact members in starting position. 60

A represents the armature or rotor of the motor having its shaft B journaled in the usual way in the motor casing C.

Secured to the armature or rotor A is a ring 1 of insulating material, surrounding 65 the armature shaft and supporting the brushes and the contact members.

2 is a metal plate rigidly secured to the insulating ring and carrying both the upper brush holder and the upper contact member. 70 The upper brush holder consists of the box or casing 3 containing a carbon brush 4, which is normally pressed against its contact ring 5, by a spiral spring 6, mounted on a screw 7 projecting from the plate 2. 75

The upper contact member 8 is pivoted at 9 to the tip of the plate 2 and has a long and comparatively heavy toe part 10, and a relatively short and light heel part 11 formed with a contacting surface 12 on its inner side. When the motor is running the centrifugal action tends to throw the toe part of the contact member 8 outward and the heel part inward, which movement is limited by a hook or projection 13 on plate 2, arranged to engage the toe part 10. 85

Another metal plate 14 is secured to the ring 1 opposite plate 2, and carries the lower brush holder and the lower contact member. The lower brush holder consists 90 of a box or casing 15, similar to the box 3, containing a carbon brush 16, pressed inwardly against the contact ring 17, by a spiral spring 18 mounted on screw 19 projecting from the plate 14. Thus the two 95 brushes, brush holders, and brush springs are substantially similar. The brush holder 15 is off set from the brush holder 3 lengthwise of the motor shaft, as shown, to bring it opposite the ring 17, and is lodged within a recess 1^a provided therefor in the ring 1. 100

The lower contact member consists of the

movable arm 20, pivoted to the plate 14 at 21, and extending in substantially a half circle around the shaft. The toe part 22 of the arm 20 is formed to engage the heel part 5 of the contact member 8. On the opposite end of arm 20 is a projection 23, to which is connected one end of a spring 24 normally tending to swing the toe part of the arm 20 inward into engagement with the contact 10 member 8. The other end of the spring 24 is fastened to a post 25 on plate 14, by means of an adjustable pin 26, threaded through the head of the post, so that the tension of the spring may be varied.

15 The two contact rings 5 and 17 are rigidly secured to the casing of the motor about the shaft, but are insulated from the ring and from each other.

Power is applied to the motor through line 20 wires or feed wires 27 and 28 which are connected to binding posts 29 and 30 respectively (Fig. 8) on the motor casing. 31 represents the running coil and 32 the starting coil. The circuit through the running coil 25 is from binding post 29 through wire 32 to the running coil and thence through wire 33 to binding post 30. The circuit through the auxiliary or starting coil is from binding post 29, through wire 34 to the starting coil, 30 thence through wire 35 to a binding post 36, thence through wire 37 to contact ring 17, thence through brush 16 and contact arm 20 to contact member 8, thence through brush 4 to contact ring 5, and thence through wire 38 35 to binding post 30 and the other main line wire.

When the motor is started the contact members are in the position shown in Figs. 1 and 8, the pivoted arm 20 being held inward by spring 24, with the toe 22 in firm contact with the heel 11 of the contact member 8, holding the toe part 10 of contact member 8 inward. Both the starting winding 32 and the running winding 31 are therefore in circuit with the line wires 27 and 28. As the motor speeds up the pivoted arm 20 tends to swing outward on its pivot by reason of the centrifugal force of rotation imparted by the rotor, and at a certain predetermined speed, depending on the tension of spring 24, the arm 20 will be thrown outward thereby breaking contact with the contact member 8 and opening the circuit through the starting winding, which is not closed again until the motor has so much slowed down as to permit the spring 24 again to draw the arm 20 inward against contact member 8. At all times during the rotation of the motor the toe part of contact 55 member 8 tends to swing outward, by centrifugal force, thus pressing the contacting surface 12 of the heel part against the toe part of arm 20, and insuring a perfect rubbing contact between the two contact members until the motor has reached such speed

that centrifugal force will overcome the spring 24, whereupon the arm 20 will be suddenly thrown outward making a quick break between the toe 22 of the arm 20 and the pivoted contact piece 8. The toe 22 will 70 be withdrawn to the position shown in Fig. 3, while the heel part 11 of contact piece 8, being freed by the withdrawal of toe 22 will permit the contact piece 8 to assume the position shown in Fig. 3 under the influence of 75 centrifugal force acting on the relatively heavy toe part 10.

As soon as the speed of the motor diminishes sufficiently to allow the spring 24 to overcome the centrifugal force acting on arm 80 20, said arm will again swing inward, until it contacts with the surface 12 of the contact member 8, and continued reduction of speed will cause the toe 22 of arm 20 to slide along said contacting surface 12, forcing the 85 heel 11 outward and finally restoring the member 8 to the position shown in Figs. 1 and 3.

Another feature of the invention is the construction of the brush holders for the carbon brushes and the spring for holding the brushes in contact with their rings. As already described, the brush holders consist of the box-like structures 3 and 15, rigidly fastened to the insulating ring 1. The brushes 90 consist of carbon blocks 4 and 16 loosely held in the brush holders and pressed toward their respective rings by their springs 6 and 18, thus making a firm contact with their contact rings and insuring a proper adjustment or take-up to compensate for wear. The springs are flat spiral springs of substantial strength but little weight, therefore having only a very slight tendency to relax their pressure on the carbon brushes under 105 centrifugal force. As the only movable parts of the brush device are the light carbon block itself and the light, flat, coil spring, the contact between the brush and its ring is only very slightly affected by centrifugal action. 110

I claim:

1. A centrifugal switch comprising a rotor, and two separable contact members, each pivotally mounted on said rotor, said contact members having mutually engaging sliding contact surfaces, one of said members being actuated by centrifugal force of rotation to move outwardly and away from the other member, and said other member being actuated by centrifugal force of rotation to tend to move inwardly and press its contact surface into close sliding engagement with the contact surface of the first member while the two members are in contact. 115

2. An electric switch comprising a rotatable support, two coacting contact members pivoted thereon and adapted to be separated by centrifugal force, and means for preventing separating of the said contact mem- 120 125 130

bers until after a predetermined amount of centrifugal force is applied, said means comprising an extension of one of the said contact members that is adapted to engage the other contact member during a portion of its separating movement.

3. An electric switch comprising a rotatable support, and two members pivoted thereon having coöperating contact faces, one of
10 which is moved inwardly under the influence

of centrifugal force tending to maintain engagement of said faces while the other is moved outwardly at a predetermined speed to separate the said faces.

Signed by me at Concord, New Hampshire, this 9th day of January, 1915.

ABE LINCOLN CUSHMAN.
